US00D844666S

(12) **United States Design Patent** (10) Patent No.: **US D844,666 S**
Espeleta et al. (45) Date of Patent: ** Apr. 2, 2019

(54) **DISPLAY SCREEN OR PORTION THEREOF WITH GRAPHICAL USER INTERFACE**

(71) Applicant: **SMULE, INC.**, San Francisco, CA (US)

(72) Inventors: **Charles Espeleta**, San Francisco, CA (US); **Jeannie Yang**, San Francisco, CA (US); **Oscar Corral**, San Francisco, CA (US); **Jonathan Moody**, San Francisco, CA (US); **Ran Xie**, San Francisco, CA (US); **Jeffrey C. Smith**, San Francisco, CA (US); **Robert Hamilton**, Palo Alto, CA (US)

(73) Assignee: **Smule, Inc.**, San Francisco, CA (US)

(**) Term: **15 Years**

(21) Appl. No.: **29/600,455**

(22) Filed: **Apr. 12, 2017**

Related U.S. Application Data

(63) Continuation-in-part of application No. 15/226,687, filed on Aug. 2, 2016, now abandoned.

(51) LOC (11) Cl. **14-04**

(57) **CLAIM**

The ornamental design for a display screen or portion thereof with graphical user interface, as shown and described.

DESCRIPTION

FIG. 1 is a front view of a first embodiment of a display screen or portion thereof with a graphical user interface showing our new design; and,

FIG. 2 is a front view of a second embodiment of a display screen or portion thereof with a graphical user interface showing our new design.

The outermost set of broken lines and the outer broken line showing of rounded shapes illustrate an electronic device. The broken line showing of all text, symbols, and icons illustrate portions of the graphical user interface. None of the broken lines form part of the claimed design.

1 Claim, 2 Drawing Sheets
